United States Patent Office

Des. 197,510
Patented Feb. 18, 1964

197,510

TRACK LAYING VEHICLE

Oliver S. Turpen, Jr., Danville, Calif., assignor to Dyna-mech Corporation, Danville, Calif., a corporation of California

Filed Apr. 12, 1962, Ser. No. 69,689

Term of patent 14 years

(Cl. D14—3)

FIG. 4.

FIGURE 1 is a perspective view taken from the front and left side of a track laying vehicle showing my new design;

FIGURE 2 is a perspective view thereof taken from the rear and right side; and

FIGURE 3 is a bottom plan view thereof on a reduced scale; and

FIGURE 4 is a fragmentary perspective view thereof.

I claim:

The ornamental design for a track laying vehicle, substantially as shown.
